UNITED STATES PATENT OFFICE.

EDGAR F. HATHAWAY, OF WELLESLEY, AND WALTER BIXBY, OF BOSTON, MASSACHUSETTS, ASSIGNEES TO SHAWMUT ENGINEERING COMPANY, OF BOSTON, MASSACHUSETTS, A CORPORATION OF MASSACHUSETTS.

YARN SPOOL FOR TUBE FRAMES.

Application filed March 7, 1923. Serial No. 623,523.

This invention relates to tube frames such as are used in weaving Axminster carpets and other similar pile fabrics and is intended to provide a construction of spool which shall afford means for interlockingly engaging the different sections of a yarn spool in operative relationship regardless of the order or sequence in which the spools are arranged, thus making the different spool sections interchangeable and reversible while providing means for rotatably supporting them for the transmission of uniform rotation of one to the other.

In the tube frames for wide looms, the yarn spools are often made in sections or short length individual spools or sections provided with journals for rotatably supporting them in bearings, said journals frequently being connected by a tenon joint or connection, the mortise being at one end of each individual spool or section and the tenon at the opposite end. The result of this right and left arrangement of the spools is that the sections can be arranged only in a fixed order with, let us say, the tenons all on the right hand end and the mortises on the left hand end, so that they are not interchangeable. The object of the present invention is to provide a simple, cheap and durable construction for rotatably supporting the spool ends in any desired sequence on the tube frame while making adequate provision for interlocking adjacent sections together so as to insure transmission of uniform rotation from one to the other as the yarn is unwound.

The invention further comprises a spool construction having concentrically arranged bearing elements of different diameter adapted to fit correspondingly dimensioned bearings of the end brackets and of the intermediate brackets of multiple spool tube frames so that, for the purpose of changing the pattern arrangement, spools may be reversed or interchanged without either bearing element interfering with the other while, at the same time, provision is made for interlocking one spool with another intermediate of one of said concentric bearing elements.

In the accompanying drawings we have illustrated applications of the principle of

this invention to the sectional spool of an ordinary tube frame, in which:

Figure 1 is a front elevation of a complete tube frame with intermediate parts 55 broken out, constructed in accordance with the principles of this invention.

Figure 2 is an end elevation of one of the spools mounted on its supporting tube frame.

Figure 3 is a longitudinal central section 60 through one end of a spool and its bearing head.

Figure 4 is a cross sectional view of the barrel of said spool.

Figure 5 is a vertical longitudinal section 65 through a modified form of head and bearing.

Figure 6 shows another modification of the spool-supporting bearing in central section. 70

Figure 7 is a similar view showing a modified construction of journal.

Figure 8 is a detail plan view of the brake with its upstanding arm shown in cross section. Figure 9 is a central section through 75 one of the bearing brackets showing the prongs of a spool journal somewhat flared to act like a brake in the bearing.

In the practice of this invention, according to the illustration of Figure 1, of the drawings, we employ any suitable form of carrier bar, in this case a tubular bar 1, of polygonal cross section to the front face of which a series of individual tuft tubes *a* are secured in any desired manner. To the ends 80 of the carrier bar 1, are secured vertical hangers 2, whose upper ends are bent to form offset upwardly projecting portions 3, adapted to penetrate the links of the carrier chain in which they are held by means of 85 hook arms 4.

The hangers 2 may be provided with any suitable ears or brackets for rotatably supporting the end journals of the yarn spool. In the present instance we have shown a 95 spool supporting ear or bracket 5, struck up integrally from one of the hanger arms 2, while the opposite end hanger 2, is provided with a spring or flexible arm 6 to support the opposite end of the sectional spool. Both 100 bearing brackets 5 and 6 are provided with female bearing elements 7, comprising a flat

disk with a peripheral laterally projecting flange which forms a female bearing for the reception of the journals of the yarn spool.

The intermediate ends of the spool sections

5 10 are rotatably supported in suitable brackets, in this case, said bearing brackets 11 being pivotally mounted in attaching straps 12, secured to the top of the carrier-bar to permit them to swing longitudinally of the 10 tube frame when removing the spool sections. Following the general practice, these intermediate spool brackets are provided with considerably larger bearings than are normally formed in the end brackets which 15 are universally provided with small bearings dimensioned to fit the outside end bearing elements of the outer yarn spools.

The spools comprise substantially cylindrical barrels 10 of appropriate length to 20 the opposite ends of which are secured disk-like heads 13. To form the journals of the spool each head is provided with a series of concentrically arranged lugs or prongs 14, which are preferably struck out of the metal 25 disk by suitable dies and are preferably formed with a peripheral curvature corresponding to the bearing openings in the brackets 11 in which they are rotatably supported. Any desired number of these arcuate bearing prongs 14 may be used, but it 30 will be observed that the spaces between the prongs are made of substantially the same circumferential width as the prongs 6 in order that similar prongs of an adjacent 35 spool may be inserted into the interstices between the prongs of its interlocking spool. Now it will be seen that if the prongs on all the spools be made of the same width 40 with the same intervening spaces, the journals will interlock or intermatch whichever end of one spool is presented to either end of any other spool. The journal prongs 14, afford sufficient bearing support to operatively support spool sections in the different bearings of the spool-supporting 45 brackets from which they may be readily removed and in which they are easily inserted. The more numerous the prongs and interstitial spaces the finer will be the range 50 of adjustment in assembling the spools. With the four prongs shown in the drawings it will be possible to adjust each spool relative to its adjacent spool by stages equal to one-quarter of a circumference, while of course double the number of prongs would provide stages of adjustment equal to one-eighth of a circumference.

Various means of securing the heads of the spool to the barrel may be employed 60 some of which are illustrated in the drawings. For example, Figure 3 shows the end of the tubular barrel 10^a provided with a transverse plate 20, formed with integral arcuate flanges 21, through which flanges is passed a diametrical screw 22 for detachably 65

securing the interior head retaining member firmly inside the hollow barrel.

The modification shown in Figure 5 employs the same construction of head 13 and of interior attaching member 21, but in this case instead of a transverse screw 22, a split stud 23 provided with a peripheral groove 24 is forced through centrally alined apertures in the head 13 and the holding plate 21, to fasten them together. The axial transverse kerf or cut along the middle line on the fastening stud allows the split portion of the stud to yield when being forced through the alined apertures and to spring out into interlocking engagement thereafter. The attaching stud 23 may also form a journal itself for use on the old style tube frames in which case the prongs 14, afford interlocking means for securing uniform rotation of the parts. Generally speaking, however, this particular construction would only be used in cases where it is desired to utilize old styles of tube frame having small journal openings for the reception of the old style journals, and in such case the prongs 14, instead of acting as a bearing journal, would form the interlocking means for securing uniform rotation of the spool sections of the tube frame.

In Figure 6 the prongs 14, instead of projecting inside of a female bearing, project outside of a bearing bushing or ring 30 which is provided with a central bearing to receive the journal stud 31 carried by the spool bracket 5. In this form the prongs 95 may have an internal bearing on the ring 30, while the ring has an internal bearing 100 on the stud 31.

Another modification of interlocking spool head is shown in Figure 7 in which is employed a spring-pressed journal member 34, mounted in a tubular attaching member 35 and normally pressed outward by a helical spring 36. This form also is intended for use in old style spool-supporting brackets 105 while providing the novel locking means for securing uniform rotation of the spool sections.

As the prongs 14 are pressed up out of sheet metal, usually sheet steel, the dies may 115 be given such design as to leave the prongs very slightly flared as shown in Figure 9, so as to make a spring friction engagement with the inside of the flange bearing members 7, to give a retarding or braking action 120 to produce a tension on the yarn instead of employing a separate spool brake.

In Figure 1 is shown a spool brake comprising a frictional pad 40 mounted on a reversely bent spring arm 41, whose lower or foot member 42 is secured to the top of the carrier bar. This arrangement gives ample flexibility and adjustment is provided as shown in Figure 8 by attaching the foot 42 of the spring brake adjustably to the carrier 125 130

bar by means of screw and slot engagement.

It will also be seen that owing to the symmetrical and similar arrangement of connecting means at each end of the individual spools each spool is reversible endwise in the frame so that either end may be presented to the right or to the left. Moreover, the construction shown and described affords a simple means for rigidly securing the end heads to the barrel by a detachable connection permitting the substitution of new heads or new barrels by effecting material economy in service. The supporting of one of the outer end bearing brackets of the spool on a spring or flexible member facilitates the easy assembling or disassembling of the spool sections in the frame.

What we claim is:

1. In a tube frame for weaving, the combination of a longitudinal carrier bar, suspension hangers and a yarn-spool rotatably supported thereby, a brake member comprising a resilient angle arm having a horizontal limb secured to the carrier bar to permit adjustment longitudinally thereof and an upright limb arranged to press against the outer face of an end head of the spool, substantially as described.

2. In a tube frame, the combination with a carrier bar and its suspension means, of a yarn spool rotatably supported thereby, a brake member comprising a reversely bent spring arm arranged to press against the outside face of a spool head and adjustable longitudinally of the carrier bar, to vary its retarding action on the spool, substantially as described.

3. In a tube frame, the combination of a carrier-bar and its suspension means, bearing brackets for rotatably supporting a yarn-spool, a yarn-carrying spool provided with resilient journal members disposed to rotate in said bearing brackets, said journal members normally acting to exert friction through their expansion against the co-operating bearings to retard rotation of the spool, substantially as described.

4. A yarn-spool for both single and multiple spool tube-frames embracing a barrel, two concentric bearing elements of different diameters located at one end thereof to fit, respectively, spool-bearing brackets having bearings of corresponding diameter, one of said bearing elements being adapted to form

interlocking engagement with the adjacent end of an aligned spool when plural spools are mounted end to end in a tube-frame.

5. In a tube frame, the combination with a carrier-bar having end bearing brackets and intermediate bearing brackets, the bearings of the intermediate brackets being substantially larger than those of the end brackets, a yarn-spool provided with supporting bearing elements of different diameters concentrically arranged, the inner bearing element being dimensioned to co-act with the end bearing bracket of the tube frame and the larger bearing element being dimensioned to fit the intermediate bearing bracket, thereby permitting the reversal or shifting of the spool in the tube-frame.

6. In a tube-frame for tuft weaving, the combination with a carrier-bar having spool-supporting end brackets and one or more intermediate brackets for rotatably supporting a series of aligned yarn-spools, the end brackets having relatively small bearings and the intermediate brackets having larger bearings, yarn-carrying spools having bearing elements dimensioned to fit the large bearings, said spools also having concentrically located bearing elements adapted to fit the small bearings of the end brackets, the outer bearing elements of the spools comprising spaced prongs concentrically arranged around the inner bearing element to provide means for interlocking two adjacent spool ends together.

7. In a tube-frame, the combination with a longitudinal carrier-bar having upwardly extending intermediate and end spool-supporting brackets provided with coaxial bearings for rotatably supporting a yarn-spool, a sectional yarn spool comprising a plurality of rotatable spool sections, each section being provided with coaxial journal members projecting from their ends and adapted to fit either the end bearing brackets or the intermediate brackets, and also to form interlocking engagement with the adjacent spool end whereby the spool sections may be mounted in the frame in any desired order in order to correspondingly vary the pattern being woven.

In witness whereof, we have subscribed the above specification.
